[57] CLAIM

The ornamental design for an optical disc player, as shown and described.

DESCRIPTION

FIG. 1 is a perspective view of an optical disc player showing my new design;

FIG. 2 is a top plan view thereof;

FIG. 3 is a rear elevational view thereof;

FIG. 4 is a left side elevational view thereof;

FIG. 5 is a front elevational view thereof;

FIG. 6 is a right side elevational view thereof;

FIG. 7 is a bottom plan view thereof; and,

FIG. 8 is a perspective view of a second embodiment of an optical disc player showing my new design;

The broken lines showing the disc tray and any other interior portion of the optical disc player are for illustrative purposes only and form no part of the claimed invention.
